COMBINED TOOTHPASTE DISPENSER, DRINKING
GLASS AND TOOTHBRUSH HOLDER

Julius A. Toth, 14263 Stansbury, Detroit, Mich.

Filed Oct. 24, 1961, Ser. No. 67,241

Term of patent 14 years

(Cl. D4—3)

FIG. 1 is a top view of a combined toothpaste dispenser, drinking glass and toothbrush holder showing my new design;

FIG. 2 is a front elevational view thereof;

FIG. 3 is a bottom plan view;

FIG. 4 is a side elevational view thereof; and

FIG. 5 is a cross sectional view taken along line 5—5 of FIG. 1.

The broken line showings in FIG. 5 are for illustrative purposes only.

I claim:

The ornamental design for a combined toothpaste dispenser, drinking glass and toothbrush holder, substantially as shown and described.
